SAFETY MEANS FOR WRINGERS

Walter L. Kauffman, II, Erie, Pa.

Application February 16, 1938, Serial No. 190,802

8 Claims. (Cl. 68—269)

This invention is designed to improve the safety feature of a power wringer. In the exemplification of the invention as herein shown this is accomplished by breaking the driving connection so as to stop the indrawing action of the rolls should an operator be caught in the rolls. The invention particularly involves a means of breaking the connection by a movement of the wringer forward and back or up and down. The up and down release is particularly effective with relation to children who may be caught in reaching up to the wringer. With the present invention the down-pull of the child so caught stops the driving action and provides a safety feature. Features and details of the invention will appear from the specification and claims.

A preferred embodiment of the invention is illustrated in the accompanying drawings as follows:

20 Fig. 1 shows a central vertical section of the power end of a wringer on the line 1—1 in Fig. 3.

Fig. 2 a front elevation of the wringer partly in section, the driving mechanism being released by a downward pull on the wringer.

25 Fig. 3 a plan view of the wringer in central or working position.

Fig. 4 a plan view, a part of the case being removed to better show construction, the driving parts being in release position through a forward 30 pulling of the wringer.

Fig. 5 a view similar to Fig. 4 but with the driving connection in section on the line 5—5 in Fig. 1.

Fig. 6 an end view of the wringer detached. 35 The wringer proper has the usual base 1, side stiles 2 (one of the stiles not being shown), top bar 3, lower and upper wringer rolls 4 and 5, lower roll bearings 6 supported by bracket 7 in the side stiles 2, said bearings receiving the lower 40 wringer roll shaft 8. Upper bearings 9 are slid- ingly mounted in the stiles, these bearings receiving an upper roll shaft 10. While only the bearings at the driving end of the wringer are shown, it will be understood that similar bearings are 45 provided in the opposite stile. A spring 11 rests on the upper bearings and a screw 12 is provided for adjusting the spring. These parts are or may be of usual construction.

The wringer is supported on a post 13. The 50 upper end of this post is provided with a swivel bearing 14 on which a gear case and wringer support 15 is mounted. A shoulder 16 at the lower end of the bearing 14 is provided with openings 17 for receiving the spring actuated locking bolt 18. By swinging the support, the wringer

may be swung to different desired positions and may be locked in the different positions by the locking bolt 18.

A drive shaft 19 extends upwardly from a source of power through the post 13, the drive shaft having a bearing 20 in the upper end of the post. The upper end of the shaft 19 is keyed to a hub 21 of a beveled gear 22. Opposing beveled gears 23 are journaled on a shaft 24. This shaft 24 is journaled in bearings 24a in the case. 5 These gears have the clutch detents 25 which are adapted to be engaged by interlocking detents 26 on the sliding clutch member 27, the sliding clutch member being splined on the shaft 24 (spline not shown). A crank pin 28 extends in a groove 29 in the clutch member 27. The crank pin is mounted on a shaft 28a journaled in a bearing 15a in the case. A handle 28b is secured to the upper end of the shaft and is provided with a spring actuated ball 28c acting on 10 detents 28d on a shoulder 28e on the case so that the clutch member is yieldingly locked in its different set positions, namely neutral, forward and reverse, three detents 28d being provided in the shoulder.

Opposing friction clutch flanges 30 and 31 have their hubs fixed on the shafts 24 and 8 respectively. These flanges are backed by ball thrust bearings 32 and 33 respectively, the ball bearing 32 being backed against the inner bearing 24a 15 and the bearing 33 being backed by a bracket 35 secured to the stile 2. An annular rib 34 is arranged on the inside of the case 15. This rib opposes the flange 35a on the bracket 35. Bolts 36 extend through the rib 34 and flange 35a at 20 intervals. Springs 37 are arranged on the bolts, preferably one spring at each end of each bolt and exert thrust from the head and nut of the bolt, drawing the flange 35a yieldingly toward the rib 34. The thrust thus provided draws the clutch flanges toward each other. Preferably a friction disc 38 is introduced between these flanges. The springs 37 are strong enough to provide a frictional engagement that will effect the driving of the wringer.

When the wringer is grasped or pulled in any direction it first brings the rib 34 and flange 35a into contact on the side corresponding to the direction of the pull. This point of contact acts as a fulcrum so that a further movement of 45 the wringer in that direction pulls the flange 35 from the rib 34 and also pulls the flange 31 out of driving engagement with the disc. This is clearly shown in Fig. 2 which indicates a separation with the down-pull on the wringer and in 50 55

Figs. 4 and 5 which indicate a separation with a side pull on the wringer.

While I have illustrated a safety device accomplished through a breaking of the driving connection, it will be understood that other forms of safety devices are contemplated in the broad phases of the invention as responding to a movement of the wringer in different directions, particularly downwardly to effect a safety action.

10. What I claim as new is:

1. In a wringer having a frame, wringer rolls in the frame, pressure means for the rolls, driving means for the rolls, and a safety device; the combination with the safety device of a support for the frame yielding for movement of the frame under normal operative thrusts forward and back and downward from operative position; and mechanism responsive to movements of the frame yielding under any of such thrusts effecting an actuation of the safety device.

2. In a wringer having a frame, wringer rolls in the frame, pressure means for the rolls, driving means for the rolls, and a safety device; the combination with the safety device of a support for the frame yielding for movement of the frame under normal operative thrusts downwardly from operative position; and mechanism responsive to movements of the frame yielding under such thrust effecting an actuation of the safety device.

3. In a wringer having a frame, wringer rolls in the frame, pressure means for the rolls, driving means for the rolls, and a safety device; the combination with the safety device of a support for the frame yielding for movement of the frame under normal operative thrusts in all directions from operative position; and mechanism responsive to movements of the frame yielding under any of such thrusts effecting an actuation of the safety device.

4. In a wringer having a frame, wringer rolls in the frame, and driving means for the rolls comprising a driving connection; the combination with the connection of a support for the frame yielding for movement of the frame under normal operative thrusts forward and back and downward from operative position; and mechanism responsive to movements of the frame

yielding under any of such thrusts breaking the connection.

5. In a wringer having a frame, wringer rolls in the frame, and driving means for the rolls comprising a driving connection; the combination with the connection of a support for the frame yielding for movement of the frame under normal operative downward thrusts from operative position; and mechanism responsive to movements of the frame yielding under such thrusts breaking the connection.

6. In a wringer having a frame, wringer rolls in the frame, and driving means for the rolls comprising a driving connection; the combination with the connection of a support for the frame yielding for movement of the frame under normal operative thrusts in all directions from operative position; and mechanism responsive to movements of the frame yielding under any of such thrusts breaking the connection.

7. In a wringer having a frame, wringer rolls in the frame, and a driving means for the wringer comprising a friction clutch with members set and released by relative axial movement; the combination with the clutch of a support for the frame comprising opposing cross-members; yielding means holding said plates against movement, said members being separable through a swinging relative movement of one end of the members, fulcrumed on the opposite ends of the members in response to movement of the wringer frame, such separation of the cross-members separating the clutch members.

8. In a wringer having a frame, wringer rolls in the frame, and a driving means for the wringer comprising a friction clutch with members set and released by relative axial movement; the combination with the clutch of a support for the frame comprising opposing cross-members; yielding means holding said plates against movement, said members being separable through a swinging relative movement of one end of the members, fulcrumed on the opposite ends of the members in response to movement of the wringer frame, said holding means exerting yielding pressure on the clutch with the wringer in set position and such separation of the cross-members separating the clutch members.

WALTER L. KAUFFMAN, II.
